UNITED STATES PATENT OFFICE.

WILLIAM S. HOGG, OF WASHINGTON, DISTRICT OF COLUMBIA.

SOUND-DIRECTION INDICATOR.

1,354,299.

Specification of Letters Patent. Patented Sept. 28, 1920.

Application filed March 14, 1919. Serial No. 282,651.

To all whom it may concern:

Be it known that I, WILLIAM STETSON Hogg, a citizen of the United States, residing at Washington, in the District of Columbia, have invented certain new and useful Improvements in Sound-Direction Indicators; and I hereby declare that the following is a full, clear, and exact description thereof, reference being had to the accompanying drawings, which form part of this specification.

This invention relates to apparatus for ascertaining the source, character and direction of sounds transmitted through air, earth or water.

Its object is to provide a simple and efficient apparatus for determining the direction of submarines, submarine bells or fog whistles. It is a means of so ascertaining, that is independent of the strength of sound received in either ear.

The apparatus in its simplest form comprises three essential elements, which may be termed generally—(1) a sound wave receiver; (2) an adjustable tuning element by which the apparatus may be adjusted to accord with the approximate wave length of any particular source of sound that one may wish to detect, and (3) a sound amplifying means connected with the tuning element.

I will first explain a simple form of the invention capable of a variety of uses, when properly proportioned, but the drawings only show embodiments of the invention, the principles of which, when once understood, can be varied in many mechanical forms, while retaining the essentials of the invention, and I refer to the claims following the description for summaries of the essentials of the invention and certain novel features of construction and arrangement of parts for all of which protection is desired.

Figure 1 represents the simplest mechanical form of the apparatus that can be held in the hand.

Fig. 2 is a plan view of Fig. 1 illustrating the electrical connections and parts diagrammatically, and also indicating in dotted lines one of the adjustments of the tuning member.

Figs. 3 and 4 are views illustrating one method of mounting the instrument on board ship, using the handle as a support. In this form the handle acts as a material communication of sound vibrations and the

receptive element to reinforce the sound variations.

The first essential element of the invention, the sound wave receiver, to be used in the air, may be shaped like a horn, a shallow box or parabolic reflector. There are many other shapes and the only essential is that they should be thin and of resonant material and capable of being vibrated upon the impact of sound waves.

I will hereinafter refer to this element of whatever shape, as the sound wave receiver, even though it may act as a resonator for more than one tone, when the reception is through the handle or support.

The horn sound wave receiver shown in Figs. 1 and 2, is of thin brass, with the ends open. The bell mouth is directed toward the source of sound and naturally has a maximum vibration when so directed. It is provided with a handle 2, attached to the small end, and at right angles to the longitudinal axis of the horn. I found that when it was so placed it received the maximum vibrations of the horn imparted to it, and vice versa when it received vibrations, so placed, the maximum strength was both imparted to the horn and tuning element. However, this fact was noted by "Savart" the French physicist in his experiments on vibrations. It is important, as it shows the method of indicating the direction of sound when communicated through the handle in communication, (material) with a ship's side or the ground, the tuning element being always at right angles to the source, when the strength of sound is a maximum, the system being tuned to resonance, with sound amplifying devices or microphones situated at loops, or points of maximum rhythmic agitation of the carbon granules.

Connected with the sound wave receiver is a tuning element 3, of resonant material, wood or metal. It may be a rod or tube, the law of longitudinal waves holding in both cases. In either case the diameter should be small, about $\frac{1}{4}$ inch for a tube, $\frac{1}{8}$ or less for a rod. If tuned to the fundamental of a horn, the lengths of metal rods are inconveniently long and mechanical arrangements of loops, circles, spirals and the like are necessary. I have found a brass tube $\frac{1}{4}$ inch external diameter to be practical. I use an Edison phonograph horn with a fundamental tone of A sharp, about 462

vibrations per second. A hollow brass tube of dimensions given 14 $\frac{1}{2}$ inches long, gives the same tone. Therefore if we attach this tube at its central point to the horn, we 5 fulfil all the necessary conditions of the vibration of bodies—that is as to the communication of such vibrations, and as the tube is at right angles to the horn, the vibrations are longitudinal as found experimentally and shown to be possible by "Savart." A horn with a fundamental of 231 vibrations would require a 29 inch tube, and this would no doubt be best for low frequencies.

15 For the sound amplifying member, I use high resistance microphones in multiple. They can be attached to the arms of a cross piece and movable along the tube or can be inserted in a cylindrical block of wood, 20 movable along the tube.

The carbon granules, held in minute double cone cavities, with large ends abutting, are the finest possible, without being dust. Contact is made with solder plugs for the 25 electric connections, and about 5 volts is necessary to put in microphonic action, 6 microphones.

To adjust the tuning element, it is clamped at its center with the clamp 5, and the microphones are moved in and out toward the center. If on both arms, as they are in phase, the effect is doubled.

The adjustment of the microphones to the fundamental of the horn is simple, both 35 practically and theoretically, as the sound is loudest when the microphones are at a loop or point of maximum rhythmic agitation of the carbon particles, as the agitation changes the carbon pressure, and the timbre 40 of the sound is brought out distinctly, so that the nature of the sound can be ascertained, and if a vessel whether surface vessel or submarine.

The receptivity of the instrument can be 45 increased by supporting the sound wave receiver by means of the handle upon the ship's rail, or upon a heavy maple sounding board inside the hull beneath the water line, the board being secured to the frames at 50 right angles. This method is not shown in the drawings. In the case shown in Figs. 3 and 4, the receptive device is shown as mounted on a support 6, pivoted upon a standard 7, journaled in a socket member 8, secured to the ship's rail. In either case 55 to lessen vibration, a sound insulating material such as felt 9, should be placed in the socket around the shoulder.

The use of the instrument is simple; move 60 it in arc horizontally, and when the sound is at maximum, the horn is pointing toward the source.

In a complete working apparatus the 65 sound amplifying members should be connected in series in an electrical circuit in-

cluding a suitable source of electricity such as a battery B; a suitable telephone receiver R, which may be of any desired kind; and an "audion" A, which may be of any suitable kind or construction adapted to amplify the sound in the well known manner. The battery, telephone receiver, and audion, are merely conventionally indicated in Fig. 2 of the drawings, as the particular construction of any of these parts does not 75 form a feature of the present invention; and such devices already well known in the arts can be used in connection with the sound detector.

The drawings only conventionally show 80 embodiments of the invention (the principles of which, when once understood, may be varied in mechanical form and dimensions while retaining the essentials of the invention) and I refer to the following claims for 85 summaries of the essentials of the invention, and of certain novel features of construction and arrangements of parts, for all of which protection is desired.

What I claim is:

1. In sound detecting apparatus of the character specified, a sound wave receiver, a tuning element connected therewith, and a sound amplifier connected with the tuning element.

2. In sound detecting apparatus of the character specified, a sound wave receiver, a tuning element connected therewith and a sound amplifier connected with the tuning element, said amplifier being adjustable relatively to the sound wave receiver.

3. Sound detecting apparatus of the character specified, comprising a sound wave receiver, a tuning element adjustably connected therewith, and a sound amplifier connected with the tuning element and adjustable relatively to the sound wave receiver.

4. In apparatus of the character specified, a sound wave receiver; an adjustable resonant tuning element mounted on the sound wave receiver at right angles thereto; and a microphone connected with the tuning element.

5. In apparatus of the character specified, a sound wave receiver; an adjustable resonant tuning element mounted on the sound wave receiver at right angles thereto; and a support at right angles to both.

6. A vibrational sound system, consisting of a sound wave receiver, a handle or support attached thereto at right angles, a tuning element connected therewith at right angles to both the sound wave receiver and handle; and a microphone attached to said tuning element.

7. In a sound detecting apparatus of the character specified, a sound wave receiver, a tuning element connected therewith, a sound amplifier connected with the tuning element, a telephone receiver, an electric sup-

- ply; and connections between the amplifier the electric supply and the telephone receiver.
8. In a sound detecting apparatus of the character specified; a sound wave receiver, a tuning element connected therewith, a sound amplifier connected with the tuning element and adjustable relatively to the sound wave receiver, a telephone receiver, an electrical supply; and electrical connections between the sound amplifier the electrical supply and the telephone receiver.
9. In a sound detecting apparatus of the character specified; a sound wave receiver; a tuning element connected therewith; a sound amplifier connected with the tuning element and adjustable relatively to the sound wave receiver; a telephonic receiver; an audion; an electrical supply; and electrical connections between the sound amplifier, the electrical supply, the audion and the telephone receiver.
10. In apparatus of the character specified; a sound wave receiver; an adjustable tuning element connected therewith at right angles thereto; a microphone connected with the tuning element; an electric supply; a telephone receiver; and electrical connections between the microphone, the supply, and the telephone receiver.
11. In combination a sound wave receiver; a variable resonant sound tuning element connected therewith at right angles thereto; microphones on said tuning element; an electric supply; an audion; a telephone receiver; and electrical connection between the microphones, the supply, the audion and the telephone receiver.
12. In apparatus of the character specified, a sound wave receiver; an adjustable resonant tuning element at right angles thereto, a support at right angles to both, a microphone connected with the tuning element, an electric supply, a telephone receiver; and electrical connections between the microphone, the supply, and the telephone receiver.
13. A vibrational sound system, consisting of a sound wave receiver; a handle or support therefor; a tuning element connected therewith at right angles to the sound wave receiver; microphones attached to said tuning element; an electrical supply; a telephone receiver; a sound amplifier and electrical connections including in circuit the 55 electrical supply, the sound amplifier, microphones and telephone receiver.
14. In combination, a sound wave receiver, a tuning element connected to said receiver at a point of maximum vibration of the material and at right angles to the axis of said sound wave receiver, a support at right angles to both, and microphones adjustably mounted on said tuning element.
15. A vibrational sound detecting apparatus consisting of a sound wave receiver which acts automatically as a resonator of several frequencies, a handle or support attached thereto at right angles to the axis of the receiver, a tuning element connected therewith at a point of maximum vibration of the material of the receiver and at right angles to both the receiver and the handle, and a microphone attached to the said tuning element; together with an electric circuit consisting of batteries and telephone receiver in circuit with the microphone.
16. A vibrational sound detecting apparatus consisting of a sound wave receiver, a tuning element at right angles to the axis of the receiver, and variable by movement laterally through a point of support which is a point of maximum vibration of the material of the receiver, and a handle at right angles to the tuning element; a telephone receiver, a microphone connected with the tuning element, an audion, an electrical supply, and electrical connections between the supply, the audion, the microphone and the receiver, substantially as described.
17. In apparatus of the character specified, a sound wave receiver, a resonant tuning element at right angles to the longitudinal axis of, mounted on the receiver and adjustable in length, and microphones movable on or attached to the tuning element.
18. In apparatus of the character specified, a sound wave receiver, an adjustable tuning element attached to or movable at right angles thereto, a microphone in material communication with the tuning element and in circuit with an electric supply and telephone receiver, with electrical connection between the microphone, the supply and telephone receiver.
- In testimony that I claim the foregoing as my own, I affix my signature.
- WILLIAM S. HOGG.
